H. JACOBS

HAIR WAVING COMB

Filed June 12, 1922

Naunah Jacobs Inventor
By her Attorney
Charles G. Hensley.

UNITED STATES PATENT OFFICE.

HANNAH JACOBS, OF BROOKLYN, NEW YORK.

HAIR-WAVING COMB.

Application filed June 12, 1922. Serial No. 567,635.

To all whom it may concern:

Be it known that I, HANNAH JACOBS, a citizen of the United States, and a resident of the borough of Brooklyn, city and State of New York, have invented certain new and useful Improvements in Hair-Waving Combs, of which the following is a specification.

The present invention relates to improvements in combs for waving the human hair and though not limited to a particular manner of use it is especially advantageous when used for making what is commonly called the "water wave." In the earlier method of making the water waves in hair a number of small individual combs were inserted one at a time into the hair and they were so manipulated that they caught the hair and moved it into wave formations and the combs were left in the hair for a time and the hair subjected to water treatment (and sometimes heat) to set the wave. In United States patents issued to Harry Jacobs and myself Nos. 1,360,643 and 1,369,974 certain improvements in combs for this purpose are shown and described, and the object of the present invention is to improve upon combs of that character.

The present device comprises a series of combs joined by articulate connections of such character that the combs move toward and from each other to compress the hair into waves and at the same time these connections cause the combs to move relatively in the direction of their length. As the combs are collapsed or moved laterally toward each other alternate combs move alternately in opposite directions lengthwise in order to hold the hair in wavy condition. In my present invention the articulate connections between the several combs are curved or arched so that when the combs are opened up they will lie in converging planes and the ends of the teeth of the device as a whole will therefore be arched to approximately conform to the curvature of the head. The result of this construction is that when the combs are inserted into the hair their teeth project therein and substantially all of them will come into contact with the scalp so that when the combs are moved toward each other they will not simply carry the outer or top portions of the body of hair along with them but will move practically all of the hair on such portion of the head as is under treatment into wave forming

position. By having the articulate connections arched in the manner described the combs automatically assume the converging condition here described without any manipulation on the part of the operator except that of moving the combs laterally. In the fullest embodiment of my invention the articulate connections are not only arched but the combs are also arched in the direction of their length in order that when the combs are in open position ready for insertion into the hair they will conform substantially to the longitudinal as well as the lateral curvature of the head. And in the preferred form the curvature of the connecting members corresponds to the curvature of the combs so that they fold up in close parallel relation thereto.

In the drawing forming part of this application:

Figure 1 is an elevation of the device showing the combs in closed or collapsed position,

Figure 2 is a side elevation showing the combs opened or extended ready for insertion into the hair.

Figure 3 is a plan view of the device showing the combs partially closed, and

Figure 4 is a perspective view showing one method of attaching the connecting members to the combs.

The device consists primarily of a plurality of combs and in the drawing I have shown six combs, 1, 2, 3, 4, 5, 6 the number and size of which may be varied. I have shown the several combs all of the same length though this is not imperative to the use of my invention. Each comb comprises a back 7 and any number and size of teeth 8 and the whole is preferably arched in the direction of the length of the comb; that is to say, the back 7 is arched and as the teeth 8 are shown as of uniform length their free ends 9 form an arched line lengthwise of the comb. This arched formation causes the teeth to conform substantially with the crosswise curvature of the head so that when the combs are inserted into the hair the teeth will all reach to or nearly to the scalp and engage all the hair on the adjacent portion of the head.

The articulate connecting members are preferably placed near each end of the combs, forming pairs, the members of each pair being parallel so that the combs move laterally in parallelism. I have shown the

members 10 connected between the ends of two adjacent combs 1, 2; the members 11, connected between the ends of adjacent combs 2, 3; and likewise the members 12, 13 and 14 connected between the ends of adjacent combs. The members 10 form a parallel pair and likewise the members 11, 12, 13 and 14 form parallel pairs, being attached near opposite ends of the respective 10 combs. Taking the members 10 they are attached at one end by pins 15 to the plates 16 on the opposite ends of the end comb 1. The other ends of these connections are pivoted to the plates 16 on the second comb 15 2 by means of pins 17. These pins 17 also form pivots for one end of the pair of connecting members 11. This construction is repeated throughout the whole device. The pins on all the combs except the end ones 20 form pivots for two connecting members while those on the end combs form pivots for one connecting member each.

The fastening members each comprise a plate having a web 18 engaging one face of 25 the back of the comb and attached to the comb by eyelets or rivets 19; and a top web 20 at right angles to the web 18 and resting against the top edge of the comb. Each plate 16 has an abutment 21 to limit the 30 swing of the connecting member but these are placed in alternate positions relatively to the adjacent pivot pins 15, 17. For instance, the abutments 21 on the plates of the endmost comb 1 are placed below the pins 35 15 in Figure 3; whereas, the abutments 21 on the plates of the next comb 2 are placed above the pivot pins 17 in Figure 3. They alternate in position on the several combs in this manner so that the pairs of connecting 40 members are compelled to swing in such manner that alternate combs will move longitudinally in opposite directions when the combs are moved laterally toward and from each other. This feature forms the subject 45 matter of my United States Patent No. 1, 369,974 and is not claimed herein except in combination.

It will be noted that each of the connecting members 10-14 is arched or curved 50 outwardly between its pivotal points, as is shown in Figures 1 and 2. In the preferred form of my invention the curvature of these connecting pieces is such that these members lie parallel with the backs of the combs 55 when the latter are in collapsed position. By reason of the curvature of the connecting members the combs, when the device opens up, lie in converging planes as shown in Figure 2. The combs lie in radial lines the 60 arc of the curvature depending upon the curvature of the several connecting members. If the device is applied to the head while in the opened position shown in Figure 2, the teeth of the several combs will 65 all reach to or approximately to the scalp

owing to the arch of the combs in the direction of the length of the device (as is shown in Figure 2) and owing to the arch shape of the several combs in the direction of their length (as shown in Figure 1) or 70 crosswise of the device.

After the device has been inserted into the hair it is folded up by pressing the combs laterally toward each other until they lie in close lateral relation. In moving in 75 toward each other the combs also move longitudinally, adjacent combs moving in reverse directions. If the combs lie in longitudinal alignment when the device is opened up then when the device is collapsed the 80 combs will assume the staggered positions shown in Figure 3 due to their relative longitudinal displacement. When the combs move laterally toward each other and longitudinally they carry the hair into position to form the desired waves. As the combs move laterally toward each other their angle of convergence changes and when they are close together they lie parallel or nearly so. As a result of this change of 85 angle the teeth of all the combs touch or nearly touch the scalp at all times, which is a very desirable result.

Having described my invention what I claim is:—

1. In a device of the class described, the combination of a plurality of combs movable laterally toward and from each other and curved links connecting said combs for causing them to lie in arched formation in 100 a direction laterally of the combs when said combs are spread apart.

2. In a device of the class described, the combination of a plurality of combs movable laterally toward and from each other and curved links connecting said combs for causing them to lie in converging planes 105 when said combs are spread apart.

3. In a device of the class described the combination of a plurality of combs movable laterally toward and from each other and curved links connecting said combs for causing them to lie in converging planes when 110 said combs are spread apart and adapted to automatically decrease the convergence of said combs as they move toward each other.

4. In a device of the class described the combination of a plurality of combs, connecting means permitting said combs to move laterally toward and from each other and adapted to cause a relative longitudinal movement of the several combs when they are moved laterally, said connecting means being constructed to cause the combs to lie in arched formation in a direction laterally 120 of the combs when said combs are spread apart.

5. In a device of the class described the combination of a plurality of combs, connecting means permitting said combs to 125

move laterally toward and from each other and adapted to cause a relative longitudinal movement of the several combs when they are moved laterally, said connecting means being constructed to cause the combs to lie in converging planes when they are spread apart.

6. In a device of the class described the combination of a plurality of combs arched in the direction of their length and means connecting said combs whereby they may be moved laterally toward and from each other and adapted to cause said combs to lie in converging planes when spread apart.

10 7. In a device of the class described the combination of a plurality of combs and arched, articulate connections permitting said combs to be moved laterally toward

and from each other and for causing said combs to lie in converging planes when spread apart.

8. In a device of the class described the combination of a plurality of combs arched in the direction of their length and articulate connecting members permitting said combs to be moved laterally toward and from each other, said articulate members being arched to lie substantially parallel with the curvature of said combs when the latter are close and adapted to cause said combs to lie in converging planes when they are spread apart.

25 30
Signed at the city, county and State of New York, this 30th day of March, 1922.

HANNAH JACOBS.
